UNITED STATES PATENT OFFICE

151,329

DESIGN FOR A DRESS

George Constantine, Brookline, Mass.

Application February 12, 1948, Serial No. 144,431

Term of patent 14 years

(Cl. D3—26)

To all whom it may concern:

Be it known that I, George Constantine, a citizen of the United States of America and a resident of the town of Brookline, in the county of Norfolk, Commonwealth of Massachusetts, have invented a new, original, and ornamental Design for a Dress, of which the following is a specification, reference being had to the accompanying drawing, forming part thereof.

Fig. 1 is a front view of a dress, showing my new design.

Fig. 2 is a back view of said dress.

I claim:

The ornamental design for a dress, substantially as shown.

GEORGE CONSTANTINE.
